UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

RADIO TUBE SOCKET.

Application filed June 5, 1924. Serial No. 718,056.

This invention relates to a socket particularly adapted for the reception of radio or audion tubes.

It is the principal object of my invention to provide a socket which will insure a continuously good contact between the spring terminals and the terminals on the tube.

It is another object of my invention to provide a socket, which is very light, yet strong and durable.

Another object of my invention is to furnish a socket in which improved means of connecting the wires to the socket terminals is provided.

Other and further objects will be apparent to one skilled in this art after a study of the specification taken in connection with the annexed drawing; wherein

Figure 1 is an end view of the socket looking at the tube entrance.

Figure 2 is a sectional view through the socket on the line 2/2 of Fig. 1.

Figure 3 is a perspective view of the moulded socket before any of the spring contacts are mounted thereon.

Figure 4 is a perspective view of an auxiliary terminal contact.

In the drawing, 1 represents the body portion of the socket having a flange 2. The flange and body portion are moulded together from some suitable insulating material, which possesses high insulating qualities and considerable strength. The flange 2 is provided with holes 3 and 4 for the purposes of mounting the socket on a panelboard 5, shown in dotted lines in Fig. 2. The ordinary audion tube has four contacts; two for the filament, one for the plate and one for the grid. Therefore, four spring contacts are provided on the particular socket illustrated. These springs are preferably arcuately spaced 90 degrees apart. The flange 2 is provided with grooves 6 for the reception of the outwardly turned ends of the spring members 7, the body portions of which springs extend longitudinally along the outer surface of the body of the socket and have their outer ends 8 bent inwardly. The ends 8 are disposed in slots 9, which act as guides for the ends 8 of the contact springs 7. As will be seen in Fig. 1, these inwardly bent ends 8 extend toward the axial center of the socket where they are engaged by the terminals of the tube which is inserted from the open end of the socket, the tube being held in place by the clip 10, provided with a bayonet lock 11. The

clip 10 lies in a slot provided in the socket and is held in position by any suitable means, such as a rivet or eyelet 12, passing radially through a portion of the flange 2. In moulding the socket, I prefer to provide, although this is not necessary, flat portions bounded by the dotted lines 13 (see Fig. 3), extending from the groove 6 to the slots 9. On these flat portions the springs 7 are normally seated. In fastening the springs 7 to the flange 2 of the socket, I prefer to utilize auxiliary terminal contacts 14, which are preferably placed over the spring contacts 7 and are fastened to the flange by screws, rivets or eyelets 15, which pass through the flange, the outwardly bent ends of springs 7 and the auxiliary terminals 14, and then being spun over as indicated in Fig. 2.

After the socket has been mounted on the panel-board 5, one end of the auxiliary contact members may be bent up as indicated at 16 for the purpose of soldering conductors thereto, or the ends 14 may be bent outwardly away from the panelboard 5 and wires connected to these ends. It is understood that these auxiliary contact members are preferably of soft drawn material so that they may be readily bent as above described.

From what has been said it will be clearly seen that the spring members 7 have their fulcrum point at the flange 2, thus providing a very resilient spring action, and on account of the bent ends 8 a relatively heavy wiping contact is provided at the terminals of the tube, which engage said spring ends.

By providing a socket of material that is not subject to changes in weather conditions as well as temperature, the spring contacts will remain in a continuous condition of operation.

While I have shown a preferred form of construction, it will be apparent that my invention is susceptible to certain changes without departing from the spirit of the same and the scope of the appended claims.

Having thus described my invention, what I claim is:

1. In a device of the class described, a socket of insulating material having a flange with mounting holes therin, said socket having spring mounting surfaces circumferentially spaced on its outer surface, said mounting surfaces terminating in slots through the wall of the socket, contact springs lying on said surfaces and each having one end bent outwardly and having an eyelet passing

therethrough and through the flange and an auxiliary contact member riveted to each contact spring by said eyelets, the other end of said contact springs being bent inwardly 5 through said slots toward the axial center of the socket, and means carried by the socket to hold a tube in contact with said inwardly bent contact ends.

2. In a device of the class described, a 10 moulded insulating socket having a flange, a tube retaining clip lying in a groove at one end of the socket and fastened to the socket by means positioned in said flange, contact springs having their body portions normally 15 resting on the periphery of the socket and having ends bent outwardly and resting in grooves on one side of said flange and fastening means going through the flange and said outwardly bent spring ends, said springs 20 having inwardly bent ends passing through

the wall of the socket toward the axial center of the socket for the purpose described.

3. In a device of the class described, a 25 socket having a mounting flange all moulded of insulating material, said flange having grooves on one side of the flange 90 degrees apart, contact springs having outwardly bent ends set in said grooves, auxiliary contact members positioned over each of said springs and an eyelet passing through said spring end 30 and auxiliary contact and flange for the purpose described, said contact springs having inturned ends near the other end of the socket and extending toward the axial center thereof, and a clip mounted on the inner surface 35 of the socket at the opposite end from said spring ends for holding a tube in contact with said inturned spring ends.

In testimony whereof, I affix my signature.
EDWARD B. NOWOSIELSKI.
